UNITED STATES PATENT OFFICE.

CHARLES FRANKISH, OF TOPEKA, KANSAS, ASSIGNOR OF ONE-HALF HIS
RIGHT TO WILLIAM GLASGOW, OF CHICAGO, ILLINOIS.

IMPROVEMENT IN MATCH-SAFES.

Specification forming part of Letters Patent No. **179,850**, dated July 18, 1876; application filed
December 18, 1875.

To all whom it may concern:

Be it known that I, CHARLES FRANKISH, of Topeka, in the county of Shawnee, State of Kansas, have invented certain Improvements in Match-Safes, of which the following is a specification describing my invention.

My invention relates to a match safe or box from which the matches are to be delivered endwise, one at a time, without removing the cover, by means of a lever operating a suitably-constructed lifter.

Referring to the drawings, Figure 1 is an outline view of the match-safe. Fig. 2 is a vertical sectional view. Fig. 3 is a view of the match-lifter. Fig. 4 is a cross-section of tube, spring, lifter, and lever.

The match-receptacle A is cylindrical in shape, having a funnel-shaped bottom, A¹, and top A². In the bottom funnel is an aperture, up through which passes the wire lifter a when actuated by the thumb-lever c c. The lifter a is embraced by a spiral spring, d, and these two are inclosed in a tube, b, having two slots, in which moves up and down the lever c, which raises the lifter by bearing on the rounded end a'. The upper side of this round end affords a shoulder upon which the spiral spring rests. The upper end of wire lifter should be serrated, as shown, to prevent the match from slipping off. Both the top and bottom are made of metal, funnel-shaped, being pressed or spun. The top is removable to allow the matches to be placed in, and has an aperture to allow the escape of the match

endwise. On the exterior of the top are springs g g, which clasp the match on its exit, and retain it from slipping back into the safe when the lever is released.

The stand or rim F I prefer to make of cast-iron, as best calculated to give it the requisite steadiness, though it may be made of wood, if desired, and covered with emery.

Match-safes having the arrangement herein described for delivering the matches endwise, one at a time, can be made in a variety of ornamental designs and styles. The plainest style may be made comparatively inexpensive.

Having described my invention, what I claim, and desire to secure by Letters Patent, is—

1. A portable match-safe having a funnel-shaped top, A², removable, and a similar-shaped bottom, A¹, with an aperture in the top for the exit of the match; the wire lifter a, spiral spring d, and thumb-lever c c, arranged as and for the purpose specified.
2. In a match-safe having a thumb-lever, such as described, to raise or eject the match, the combination, with the funnel-shaped top A², of the two springs g g, secured thereto on opposite sides of the aperture for the exit of the match, for the purpose specified.

CHARLES FRANKISH.
